UNITED STATES PATENT OFFICE.

HOMER E. RAWSON, OF CHICAGO, ILLINOIS.

STEEL FISHING-ROD.

1,385,149.

Specification of Letters Patent. Patented May 19, 1921.

Application filed March 21, 1921. Serial No. 454,068.

To all whom it may concern:

Be it known that I, HOMER E. RAWSON, a citizen of the United States, and a resident of Chicago, in the county of Cook and State 5 of Illinois, have invented a new and useful Improvement in Steel Fishing-Rods, of which the following is a full, clear, and exact description.

My invention relates to improvements in 10 steel fishing rods, and it consists in the combinations, constructions and arrangements herein described and claimed.

An object of my invention is to provide a 15 steel fishing rod comprising a plurality of sections of various lengths relatively arranged in such a manner that the weight and resistance in a rod of a given size are distributed to afford ease of handling.

A further object of my invention is to 20 provide a device of the character described having means for resisting and distributing the stress placed thereon in service to insure the yielding of a steel rod uniformly along its length so that a greater 25 strain is not produced at one point than at another.

A further object of my invention is to 30 provide a device of the character described in which the resistance in a rod of a given length and made of a given material is distributed to insure a desired flexibility of the rod in service.

A further object of my invention is to 35 provide a device of the character described having means for strengthening the device at the points subjected to the greatest stress in service without impairing the flexibility of the device and without impairing the balanced distribution of the weight thereof.

0 A further object of my invention is to provide a device of the character described that embodies a novel joint construction.

Other objects and advantages will appear in the following specification, and the novel 5 features of the invention will be particularly pointed out in the appended claims.

My invention is illustrated in the accompanying drawings, forming part of this application, in which—

0 Figure 1 is a side elevation of the device, Fig. 2 is a side elevation of the tip section thereof,

Fig. 3 is a similar view of the middle section,

5 Fig. 4 is a similar view of the butt end section,

Fig. 5 is an enlarged sectional view longitudinally through a fragmentary portion of the outer end or tip joint or section, and

Fig. 6 is a similar view showing a section 60 through a fragmentary portion of the intermediate section.

In steel rods of which I am aware, the sections or joints, as they are commonly called, are approximately equal in length. 65 As a result, a rod of a given size and made of steel does not have the flexibility desired and the distribution of the weight thereof is not such as to promote ease of handling. Furthermore, in rods of an ordinary construction, a greater strain results in service at a point in advance of the connection of each joint with the adjacent joint so that the rod yields or bends in an irregular line and is liable to break at the points of maximum strain. A device embodying my invention bends or yields in a uniformly curved line and consequently is not liable to break. 70 The yielding of the rod in a uniform manner permits the device to be used more effectively in casting and the distribution of the weight in a rod of a given size is such as to make the device capable of being handled conveniently.

In carrying out my invention, I provide a 85 rod comprising a tip section or joint 1, an intermediate or second joint 2, and a butt end joint 3 that is adapted to engage with a handle 4. The sections or joints are made of a metal that is sufficiently flexible and 90 strong inherently, such as steel, and are provided with the usual offset ring guides, indicated at 5. The handle 4 is ordinary in construction and may be of any suitable 95 type.

The tip section 1 is considerably longer than the intermediate or second section 2. The latter is considerably longer than the butt end section 3. In a four and a half foot rod, such as I have illustrated, the tip section is approximately 33½% longer than the second section and the second section is approximately 50% longer than the butt end section. The lengths will vary somewhat with the size of the rod and with the 100 material used in the manufacture of the same but I find that the lengths given are preferable for a steel rod of the size stated.

The tip section 1 has secured in the bore 6 thereof an inner strengthening member 7 that is preferably tubular as shown. The strengthening member 7 is disposed adjacent 110

to the end of the section 1 that is adapted to engage with the outer end of the second section 2, the junction being effected by the fit of a ferrule 8 of the section 1 in a socket 9 of the section 2. It is to be noted that the inner end of the member 7, that is, the end adjacent to the section 2, extends to the corresponding end of the ferrule 8. An outer tubular strengthening sleeve 10 secured on 10 the tip section 1 has its end adjacent to the section 2 arranged to underlie a shoulder 11 that is integral with the ferrule 8, being beveled at its end at 12 to engage the contiguous wall of the shoulder. The outer 15 strengthening sleeve 10 tapers at its other end to underlie a holder 13 supporting the adjacent ring guide. It will thus be obvious that the section 1 has the appearance of a corresponding section in an ordinary rod 20 since the ends of the outer sleeve 10 are concealed.

The second joint or section 2 is provided with an inner strengthening member 14 that corresponds to the inner strengthening member 25 7 and is arranged relative to the ferrule 15 that is mounted on the section 2 at the end thereof and is adapted to fit within a socket 16 in the end of the section 3. The latter is provided with a ferrule 17 at its 30 other end adapted to fit within a socket 18 in the end of the handle 4.

From the foregoing description of the device, the operation thereof may be readily understood. The device is reinforced at 35 the points at which the greatest stress is imposed, that is, at points slightly in advance of the ferrules of the second and tip joints. On account of the lengths of the relatively arranged sections being unequal in a rod 40 embodying my invention, the provision of

the reinforcing members does not impair the flexibility of the device, as would be the case if the construction were ordinary. The strain is uniform along the length of the rod and the latter is strengthened at the points 45 subjected to the greatest stress without sacrificing flexibility. In a rod of a given size and weight, the center of gravity is positioned nearer the handle in my device than is ordinary and consequently the weight 50 of my device appears to be less than that of the ordinary device.

I claim:

1. A device of the character described comprising a plurality of sections of various 55 lengths adapted to be connected in alinement with one another.

2. A fishing rod comprising a handle and a plurality of sections adapted to be joined in alinement with one another and to handle, 60 said sections being formed in progressively increased lengths from the handle to the tip of the rod.

3. A fishing rod comprising a handle and a plurality of sections made of steel, said 65 sections being adapted to be connected to one another and to the handle in a longitudinal series and being formed in progressively increased lengths.

4. A fishing rod comprising a handle, a 70 butt end section, a second section, and a tip section, said sections being formed of steel being provided in progressively increased lengths, and being each adapted for connection with the adjacent section and in alinement therewith, said tip section and said second section each being reinforced adjacent to its rearward end.

HOMER E. RAWSON.
